UNITED STATES PATENT OFFICE.

FRANK CONRAD, OF PITTSBURGH, PENNSYLVANIA, ASSIGNOR TO WESTINGHOUSE ELECTRIC & MANUFACTURING COMPANY, A CORPORATION OF PENNSYLVANIA.

WIRELESS TRANSMISSION SYSTEM.

Application filed March 10, 1922. Serial No. 542,690.

My invention relates to wireless transmission systems and it has particular relation to arc-converter systems.

An object of my invention is to provide a system in which a centrally disposed arc-generator may be employed to simultaneously energize a plurality of multiple-tuned antennæ which are grouped about a central point.

10 In high-power, long-distance wireless transmission systems, it is common practice to employ a relatively low antenna which extends for long distances substantially parallel to the surface of the earth. An important disadvantage of the type of antenna just mentioned is the large resistance losses caused by the heavy charging currents supplying the extreme portions of the antenna. Another important disadvantage of such 15 high-power antenna systems arises from the fact that their high apparent resistance renders them unsuited for the employment of arc oscillators of usual construction.

An object of my invention, therefore, is to provide means whereby an arc system may be employed in connection with a plurality of multiple-tuned antennæ.

Another object of my invention is to provide means for varying the apparent resistance of a group of multiple-tuned antennæ whereby the antenna system may be adjusted to the critical resistance required for maximum efficiency in connection with an arc oscillator.

35 Other objects, as well as the details of construction, whereby my invention may be carried out, will be apparent from the following description and claims when read in connection with the accompanying drawings, wherein.

Figure 1 is a diagrammatic perspective view of circuits and apparatus embodying my invention, and

45 Figs. 2 and 3 are similar views illustrating alternative arrangements.

According to my invention, I provide an antenna system comprising a group of preferably small, insulated, non-parallel antennæ, each having a separate ground connection and tuning coil. In Fig. 1, I have illustrated the antenna system as comprising a group of non-parallel antennæ 5, 6, 7, arranged in star formation. In Fig. 2, the antennæ 5, 6, 7 are shown in delta formation. Fig. 3 shows a square arrangement employ-

ing four separate antennæ 5, 6, 7, and 8. The ground connections and tuning coils are indicated, respectively, at 9 and 10. The antennæ may be insulated one from another by insulators 11 which may be carried by towers 12.

If any one of the antennæ circuits, such as the antenna 5, and its tuning coil 10 and ground connection 9, is set in oscillation, and the other antennæ are tuned to the same frequency, oscillations may be induced in the last mentioned antennæ by means of conductors connecting any point of the first oscillating system, having a potential different from ground potential, to a corresponding point in each of the other circuits. The interconnections between the various circuits may be easily made by means of conductors 13 connecting intermediate taps 14 on the tuning coils 10, as illustrated in Figs. 1 and 2. In the modification shown in Fig. 3, the interconnecting conductors 13 are connected to coils 15 which are inductively associated with the respective tuning coils 10.

I have shown an arc oscillator 16 as a source of oscillating currents. The oscillator includes an arc 17 connected in circuit between the tuning coil and ground connection 9 of the antenna 5. The arc may be energized by means of a direct-current generator 18 connected thereto through choking coils 19, and the oscillations may be modulated by any means (not shown), as will be readily understood.

Assuming that the antenna circuit 5 is oscillating and that the interconnecting conductors 13 are disconnected, there will be a drop of potential from a maximum value at the top of the tuning coil 10 to the bottom of the tuning coil. The oscillating current will be composed of a small component, that may be called the power component, which supplies the various losses, such as ohmic and radiation losses, and a large wattless component.

When the interconnecting conductors 13 are connected to the taps 14 of the various tuning coils, it will be necessary for small currents to traverse the interconnecting conductors in order to supply the losses in the antennæ which are not directly connected to the arc oscillator. It is apparent, however, that the currents flowing in the conductors 13 become larger as the tap points 14 are moved downward, thereby decreasing the po-

tential. Hence, the total current flowing through the arc 17 becomes larger as the tap points are moved downward, while the voltage across the arc remains substantially constant, thus producing an effect of decreasing the resistance of the oscillating circuits connected to said arc.

In my copending application, Serial No. 430,630, filed December 14, 1920, I have disclosed a similar antenna system in which the arc oscillator 16 is omitted and a source of oscillations is connected between the interconnecting conductor 13 and the ground. With this connection, the source of oscillation is traversed only by the energy components of the oscillating currents, whereas, in the present application, as above pointed out, the arc 17 carries a current in excess of the total oscillating current in the antenna. 5. Since it is necessary that the arc of an arc oscillator shall be shunted by a tuned oscillating circuit, the direct inclusion of the arc in circuit with one of the antennæ ground connections, as illustrated in the present application, is desirable in that it avoids the necessity for the employment of separate tuning condensers in the arc circuit, which would be necessary if the arc were connected as shown in my copending application. 10. In the arrangement shown in the present application, it is understood, of course, that stopping condensers 20 will be provided for preventing the short-circuiting of the direct-current source 18. In Fig. 1, a single stopping condenser 20 is shown in the ground connection of antenna 5 between the tuning coil 10 and the ground 9. In Fig. 2, a stopping condenser 21 is placed in each of the interconnecting conductors 13. In Fig. 15. 3, a stopping condenser 22 is placed in the ground connection of each of the antennæ 6, 7 and 8.

By disposing the tuning coils or power transformers directly beneath the antennæ, I am enabled to energize the several antennæ at relatively low voltages which, in an arc system, is a decided advantage. A further advantage of this system of distribution is that the usual corona losses in the conductors extending from the source of power to the antenna are reduced to a minimum.

Another advantage is the provision of a radiating system in which the phase displacement of the waves radiated by the several antenna (with respect to each other) is substantially zero.

The particular advantage of my invention, however, is in the provision of means whereby a plurality of antennæ may be energized from a single arc-converter system, which may or may not be included directly in one of the antenna ground-leads.

While I have shown three embodiments of my invention, it is obvious, to one skilled in the art, that various modifications may be

made both in the arrangement of the antenna and in the disposition of the stopping condensers without departing from the spirit and scope of my invention. I desire, therefore, that only such limitations shall be imposed thereon as are indicated in the appended claims.

I claim as my invention:

1. In a wireless transmission system, the combination with a plurality of antenna circuits tuned to the same frequency, of a source of oscillations included in one of said circuits, and connections between points having like potentials in the several circuits, whereby all of said circuits are caused to oscillate in unison. 75

2. In a wireless transmission system, the combination with a plurality of antenna circuits tuned to the same frequency, of an arc oscillator included in one of said circuits, and connections between points having like potentials in the several circuits, whereby all of said circuits are caused to oscillate in unison. 80

3. In a wireless sending station, the combination with a main oscillating circuit, of a second oscillating circuit, a source at said station of oscillations for said first-mentioned circuit, and a conductor connecting points of like potential in the respective circuits, said connecting points being adjustable, whereby the apparent resistance of said second oscillating circuit may be varied. 90

4. In a wireless signaling system, the combination with a plurality of non-parallel antennæ and an arc-converter system, of separate tuning means for each antenna and means whereby each antenna may be energized from said arc-converter system. 100

5. In a wireless signaling system, a plurality of non-parallel antennæ, a ground-lead for each antenna, means included in each ground-lead whereby each antenna may be separately tuned, an arc-converter system and means whereby each antenna may be energized from said arc-converter system. 110

6. In a wireless signaling system, a plurality of antennæ so grouped about a central point that the greatest distance between two antenna ends is less than the sum of the distances between the ends of the several antennæ, a ground lead for each antenna, means included in each ground lead whereby each antenna may be separately tuned, a single arc-converter system and means whereby said plurality of antennæ may be energized from said arc-converter system. 115

7. In a wireless signaling system, a plurality of antennæ so grouped about a central point that the greatest distance between two antenna ends is less than the sum of the distances between the ends of the several

antennæ, a ground-lead for each antenna, a tuning coil for each antenna, a single source of energy, and means including said tuning coils for energizing all of said antenna from said source.

8. A wireless signaling system comprising a plurality of non-parallel radiating antennæ systems, each antenna system being tuned to substantially the same frequency, an arc converter included in one of said antennæ systems and means for operatively connecting the remaining antennæ systems to said arc-converter, said means including means for preventing the flow of direct current.

9. In a wireless signaling system, a plurality of radiating antennæ, a plurality of towers for supporting said antennæ, said antennæ extending radially outwardly from one of said supporting towers, a

ground-lead circuit for each antenna and including therein an inductance coil, an arc-converter included in one of said ground-lead circuits, and means whereby said plurality of antennæ may be energized substantially simultaneously from said arc-converter.

10. In a wireless signaling system, a plurality of non-parallel antennæ, a ground-lead for each antenna, means included in each ground-lead whereby each antenna may be separately tuned, a single arc-converter system and means whereby each antenna may be energized from said arc-converter system.

In testimony whereof, I have hereunto subscribed my name this 4th day of March, 1922.

FRANK CONRAD.
